CLAIM

The ornamental design for a garment, as shown and described.

DESCRIPTION

FIG. 1 is a front perspective view of a garment showing my new design;

FIG. 2 is a front view thereof;

FIG. 3 is a rear view thereof;

FIG. 4 is a left side view thereof;

FIG. 5 is a right side view thereof;

FIG. 6 is an enlarged view of the encircled portion A indicated in FIG. 1;

FIG. 7 is an enlarged view of the encircled portion B indicated in FIG. 2;

FIG. 8 is a front perspective view of a garment showing my new design in an alternative embodiment;

FIG. 9 is a front view thereof;

FIG. 10 is a rear view thereof;

FIG. 11 is a left side view thereof; and,

FIG. 12 is a right side view thereof.

The even-length broken lines represent stitching and form no part of the claimed design.

The broken lines depicting the icons on the controller form no part of the claimed design.

1 Claim, 12 Drawing Sheets
